UNITED STATES PATENT OFFICE.

EDWARD DAVID ASHE, OF BROMPTON, COUNTY OF MIDDLESEX, ENGLAND.

IMPROVEMENT IN PROPELLER-ENGINES.

Specification forming part of Letters Patent No. 42,336, dated April 19, 1864.

To all whom it may concern:

Be it known that I, EDWARD DAVID ASHE, of Brompton, in the county of Middlesex, in that part of the United Kingdom of Great Britain and Ireland known as England, a lieutenant in Her Britannic Majesty's navy, at present stationed at Quebec, in the Province of Canada, have invented a new and useful Improvement in Marine Steam-Engines for Driving Propellers; and I do hereby declare that the following is a full, clear, and exact description of the same, reference being had to the accompanying drawings, forming part of this specification, in which—

Figure 1 is a plan of a steam engine for driving a screw-propeller having my invention applied to obtain the rotary motion of its shaft from the reciprocatory motion of its pistons. Fig. 2 is a longitudinal view of the shaft, taken at right angles to Fig. 1. Fig. 3 is a face view of one of the drivers.

Similar letters of reference indicate corresponding parts in the several figures.

The principal object of my invention is to obtain a high velocity of shaft without gearing, or, in other words, to obtain two or more revolutions of the shaft of an engine from one stroke of the piston; and it consists in a certain construction and arrangement of a spirally-grooved shaft, in combination with drivers attached to the piston-rods for this purpose.

To enable others skilled in the art to make and use my invention, I will proceed to describe its construction and operation.

A A' are two steam-cylinders, arranged side by side as near together as may be desired, and having their piston-rods *a a'* furnished at their outer ends with sliding blocks *b b'* to work in guides in a frame, C.

B is the propeller-shaft, arranged in suitable bearings in the frame C, parallel with the cylinders and midway between their piston-rods. One end may be nearly close to the cylinder-heads. The portion of the shaft between the bearings is enlarged in cylindrical form, and has provided in it two grooves, *d d'*, which run spirally round it in opposite directions at an angle of about forty-five degrees to the axis of the shaft, the said grooves both starting from the same point *e*, making two complete revolutions around the shaft, crossing each other in three places, as shown at *f*,

j, and *k*, and each terminating in the other at *g*.

h h are what I call "drivers," made with tongues *i i* to fit and work freely in the grooves *d d'*, and having the sides of the said tongues curved in such manner (shown in Fig. 3) as to permit them to turn freely at the junctions *e* and *g* of the grooves, and pass from one groove into the other. These drivers are made with pivots *n n*, which are fitted into the sliding blocks *b b'* in such manner as to be capable of turning or oscillating freely.

By the reciprocating movements of the pistons the drivers *h h* are caused to travel the whole length of one groove, then to turn into and return along the other, and in so doing they produce a rotary motion of the shaft, producing two complete revolutions thereof at each stroke of the piston, or four revolutions for one stroke back and forth. The two drivers are so arranged that they will never both arrive at the ends of the grooves together, and consequently that the pistons will never both be at the end of their stroke at the same time.

By extending the grooves *d d'* to make more than two revolutions round the shaft, and giving the pistons a corresponding length of stroke, more than two revolutions of the shaft may be obtained by each stroke of the piston in either direction. This mode of construction, besides serving to obtain a high velocity without gearing, enables the working parts of an engine to be brought within a very small compass, which renders it applicable with especial advantage to screw propulsion. The smallness of compass results from the arrangement of the shaft in the space between the two piston-rods, which would otherwise be wasted.

I do not claim, broadly, the employment for the purpose of obtaining rotary motion of a spirally-grooved cylinder.

I am aware that it is common to convert reciprocating rectilinear into rotary motion, and vice versa, by the use of slides or drivers working in spiral grooves on the shaft, and, further, that in printing-presses and some other machines a plurality of spiral grooves are employed, passing several times around the shaft.

My invention relates exclusively to marine engines for propelling vessels; and

What I claim as new therein, and desire to secure by Letters Patent, is—

The combination of the two engine-cylinders A A', piston rods a a', guides b b', drivers h h', ways C C, and propeller-shaft B, formed with a plurality of intersecting spiral grooves d d', having two or more revolutions, when the said drivers h work on opposite sides of the

said shaft B, one in each of the grooves d d', and all the parts are constructed and arranged to operate in the manner and for the purposes herein specified.

EDWARD DAVID ASHE.
